BATHING SUIT

Frank Torok, New York, N. Y., assignor to Artistic Foundations, Inc, New York, N. Y.

Application September 16, 1949, Serial No. 5,033

Term of patent 3½ years

(Cl. D3—17)

To all whom it may concern:

Be it known that I, Frank Torok, a citizen of the United States of America and a resident of the city of New York, county of New York and State of New York, have invented a new, original, and ornamental Design for Bathing Suit, of which the following is a specification, reference being had to the accompanying drawing, forming part thereof in which—

Fig. 1 is a front view of a bathing suit, embodying my new design.

Fig. 2 is a rear view thereof.

I claim:

The ornamental design for a bathing suit, as shown.

FRANK TOROK.
